UNITED STATES PATENT OFFICE.

JEREMIAH J. KELLEHER AND CHARLES D. PORTER, OF PHILADELPHIA, PENNSYLVANIA.

CAR-ROOF CONSTRUCTION.

1,022,091.

Specification of Letters Patent.

Patented Apr. 2, 1912.

Application filed November 8, 1911. Serial No. 659,090.

To all whom it may concern:

Be it known that we, JEREMIAH J. KELLEHER and CHARLES D. PORTER, citizens of the United States, residing at Philadelphia, 5 county of Philadelphia, and State of Pennsylvania, have invented certain new and useful Improvements in Car-Roof Construction, of which the following is a specification.

10 Our invention relates to improvements in car roof construction, the object of the invention being to provide a car roof which will embody the maximum of strength and durability, and which will perfectly exclude 15 water.

A further object is to provide an improved arrangement of carline and cap transversely positioned on opposite sides of the roof timbers and having filler pieces, all 20 of which are secured by bolts passed through the carline, cap, filler pieces and roof timbers.

25 A further object is to provide improved means for securing and confining the edges of metal roof sheets, and provide an improved construction of saddle for supporting the running boards on top of the car.

With these and other objects in view, the 30 invention consists in certain novel features of construction and combinations and arrangements of parts, as will be more fully hereinafter described and pointed out in the claim.

In the accompanying drawings, Figure 1, 35 is a fragmentary top plan view illustrating our improvements. Fig. 2 is a view in transverse section on an enlarged scale on the line 2—2 of Fig. 1. Fig. 3, is a view in transverse section on an enlarged scale 40 on the line 3—3 of Fig. 1. Fig. 4, is a fragmentary view in side elevation illustrating two of the eave clips in place and one removed. Fig. 5, is a fragmentary view on an enlarged scale in longitudinal section on 45 the line 5—5 of Fig. 1. Fig. 6, is a fragmentary view in section on the line 6—6 of Fig. 1. Fig. 7, is an inner face view of one of the eave clips. Fig. 8, is an end elevation of one of the eave clips. Fig. 9, is a view in section on the line 9—9 of Fig. 7. Fig. 10, is a view in section on the line 50 10—10 of Fig. 7. Fig. 11, is a view similar to Fig. 2 but illustrating a modification, and Fig. 12, is an enlarged view in section on the line 12—12 of Fig. 11.

A longitudinal series of transversely po-

sitioned channel bars or carlines 1 are secured at their ends to longitudinal side beams 2 by means of bolts 3. The ends of the carlines have laterally projecting perforated plates 4 integral with the carlines, and through which the bolts 3 project, and are secured by nuts 5. The carlines are arched to conform to the shape of the roof, and contain filler pieces 6 of wood. To 60 these filler pieces, the roof timbers 7 are secured by nails 8, and covering the heads of these nails are transversely positioned filler pieces 9 which are curved transversely on their outer faces, and on their inner faces 70 are flat, and lie against and across the roof timbers 7. Metal caps 10 are positioned on the cap filler pieces 9, and at their lower ends are curved outwardly so as not to present any sharp edges which might cut when any 75 motion is given the timbers. These caps 10 are approximately inverted U-shape in cross section, and extend throughout the width of the car directly above the carline 80 1, and they also confine the longitudinal edges of roof plates 11. These roof plates are of sheet metal, and their longitudinal edges extend over the filler pieces 9 under the caps 10, and said caps 10, filler pieces 9, 85 filler pieces 6, and carlines 1, together with 90 the roof timbers 7, are made with registering openings for the reception of bolts 12. The heads 13 of these bolts bear tightly against flattened surfaces 14 on the caps 10, which flattened surfaces are formed by forcing the metal outwardly to form the openings, and the said bolts are securely clamped by nuts 15 on their inner ends.

By tightening the nuts 15, the roof timbers 7, as well as the roof plate 11 are securely clamped, and the structure is therefore strong and durable. As the filler pieces 9 cover the nails 8, the latter cannot work 95 loose, and are securely held in driven position.

100 On the crown of the roof, on each cap 10, a metal saddle 16 is located. Each saddle comprises a casting having its lower face inclined downwardly in both directions transversely from its center, and curved in the arc of a circle longitudinally of the car to snugly fit the cap 10 as seen most clearly in Figs. 2, 3, and 5. These saddles are secured to the roof structure by bolts 17, 105 which are projected through the lower inclined members 18 of the saddle, and are secured by nuts 19. The upper portion of

the saddle is horizontal, and is provided with four upwardly projecting lugs 20 between which the parallel running boards 21 are located. These running boards are secured 5 against movement by long bolts 22, which extend through registering openings in the lugs 20, and in the running boards 21, and are secured by nuts 23. It will therefore be seen that the upper surface of the running board is free from bolt heads, and the like, as the boards are secured entirely by means of the transversely positioned bolts 22. This is a decided advantage because this upper surface must be kept smooth. 10 15 The ends of the roof sheets or plates 11 are curved around rods 12^a. These rods 12^a are of slightly greater length than that portion of the sheet which extends over the side edges of the car, so that the ends of the rods project beyond the edges of the metal plates as seen most clearly at the right of Fig. 4. 20 25 To confine and securely hold the adjacent ends of the rods 12, as well as the sheets or plates 11 and caps 10, we employ what we term "eave clips" 24 which are illustrated in detail in Figs. 7, 8, 9, and 10, and in operation in Fig. 4. These clips each comprise a casting which has an upper restricted 30 hood 25 to inclose the end of the cap 10 and filler piece 9. The upper portion of the clip, adjacent the restricted hood, is inclined to conform to the shape of the sheets 1, as they extend over the roof and around the rods, 35 but said clips are made with partitions 26 which are positioned between the adjacent ends of the rods 12^a, so as to securely hold said rods against longitudinal movement. The lower portion of each clip is flat, and 40 lies flat against the fascia board 27 of the car, the side timbers 28 being confined between these fascia boards, and the side timbers 2 by means of the bolts 3 above referred to. The said bolts 3 also project through openings 29 in the clips, and securely hold the 45 clips in position.

Corner brackets 30 confine the corners of

the roof structure and the running boards 21 extend out over the end of the car, and are secured to transverse timbers 31, and to 50 brackets 32 by bolts 33 and nuts 34.

In Figs. 11 and 12 we illustrate a modification in which the cap 35, saddle 36, and eave clips 37 are all formed of a single integral casting. These parts are of the same 55 general shape and for the same purpose as the similar parts of the preferred form above described, except that they are all integral and bolts 38 are secured in enlargements 39 on the inner faces of the caps, and 60 are therefore rigidly secured to the caps and assembled with the caps.

Various other slight changes might be made in the general form and arrangement of parts described without departing from 65 our invention, and hence we do not limit ourselves to the precise details set forth, but consider ourselves at liberty to make such changes and alterations as fairly fall 70 within the spirit and scope of the appended claim.

Having thus described our invention, what we claim as new and desire to secure by Letters Patent is:

In combination with roof timbers and 75 transversely positioned cap plates on said timbers, of roof sheets located on the timbers and having their edges confined beneath the cap pieces and their ends projecting over the edges of the roof, rods 80 around which the ends of said plates are bent, the ends of said rods projecting beyond the plates, and eave clips confining the ends of said rods, the edges of said plates, and the ends of said caps. 85

In testimony whereof we have signed our names to this specification in the presence of two subscribing witnesses.

JEREMIAH J. KELLEHER.
CHARLES D. PORTER.
